UNITED STATES PATENT OFFICE.

ERNEST WALLISER, OF PHILADELPHIA, PENNSYLVANIA.

DESIGN FOR FRINGE.

SPECIFICATION forming part of Design No. 24,097, dated March 12, 1895.

Application filed December 29, 1894. Serial No. 533,354. Term of patent 3½ years.

To all whom it may concern:

Be it known that I, ERNEST WALLISER, a citizen of the United States, residing in the city and county of Philadelphia, State of Pennsylvania, have invented and produced a new and original Design for Fringe, of which the following is a specification, reference being had to the accompanying drawing, forming part thereof.

10 The leading feature of my design for a fringe is the body of the same composed of tufts and filaments, and of a striped nature.

In the drawing: A designates the body of the piece of chenille fringe, the same being

formed of the tufts B, and filaments C intermingled therewith, said body being also formed in stripes D, E, and F, said filaments having projecting ends which extend outwardly from the central line of fringe among the said tufts.

15 What I claim is—

The design for a fringe, substantially as described and shown.

ERNEST WALLISER.
